UNITED STATES PATENT OFFICE.

GEORGE E. MUSEBECK, OF MILWAUKEE, WISCONSIN, ASSIGNOR, BY MESNE ASSIGNMENTS, TO WILLIAM T. EDMONDS, OF MILWAUKEE, WISCONSIN.

SHOE.

Application filed January 29, 1923. Serial No. 615,640.

This invention has for its object to improve upon the construction of leather shoes by giving permanency to the shape of the insole so as to afford a bearing surface for the 5 foot shaped on the last to fit the foot and retaining such shape and fit throughout the life of the shoe.

Another object of the invention incident to the foregoing is the avoidance of what is 10 known as "running over" consisting of a lateral displacement of the foot, causing it to overhang the edge of the sole. This object is accomplished by the permanency of the recess forming the bearing for the ball of the 15 foot, serving to confine the foot in place against such displacement.

Another object of the invention is to avoid 20 the development of raised ridges along the seams incident to the displacement by wear 20 of the usual composition filler between the inner and outer soles.

Another object of the invention is to prolong 25 the life of the shoe and to give greater ease and comfort to the wearer by flattening the sole beneath the ball of the foot and so enlarging the area of the bearing surface.

With the above and other objects in view 30 the invention consists of the shoe as herein claimed and all equivalents.

Referring to the accompanying drawings, 35 in which like characters of reference indicate like parts in different views,

Fig. 1 is a perspective view of a shoe constructed in accordance with this invention, 40 dissected on its last to show the sections thereof;

Fig. 2 is a transverse section showing the 45 appearance of the shoe before the outsole is applied, the dotted line showing the amount of the insole buffed away to permit it to fit flatly against the outsole and to produce the wedge-like tapering thickness of the insole around the location of the bearing for the ball of the foot;

Fig. 3 is a transverse sectional view of the 50 insole showing the extra heavy material used to permit of the heavy buffing operation and to afford the solid foundation for the molded seat for the foot;

Fig. 4 is a transverse sectional view of the 55 completed shoe on its last;

Fig. 5 is a longitudinal sectional view of a 60 part of the shoe on its last.

In these drawings, 10 indicates a last to

which is fitted an insole 11 and the upper 12 55 in the usual manner, the insole, however, being of much greater thickness than is usual either as a single piece or of built-up construction. In practice it is found desirable to use a very heavy insole of outsole leather, known as 60 about seven-iron thickness, in order that it may be buffed away to a material depth at the high spot of the last corresponding with the great toe joint of the foot. This buffing operation is performed after the insole has 65 been stitched to the upper, as in Fig. 2, and after a triangular sole leather welt 9 has been cemented in the channeled groove, as shown in this figure. The buffing operation is continued to remove the protruding portion of 70 the insole that is caused by the high spot of the pattern corresponding with the ball of the foot and until the parts are brought to a flat condition across the entire width of the shoe. This, of course, varies the thickness 75 of the insole so that it is quite thin directly beneath the ball of the foot and increases in thickness in all directions from that point so as to produce in effect a solid wedge-like support for the foot on either side of said 80 point, as shown in Fig. 4, and to the front and rear thereof, as shown in Fig. 5.

The use of an extra heavy insole makes it 85 possible to buff away in this manner to obtain the solid molded support for the foot without 90 damaging the insole and it also permits of a heavy shouldered channel 13 to which the upper 12 and welt 15 are attached.

The outsole 14 is stitched to the welt 15 in 95 the usual manner, but, because of the insole having been buffed flush with the edges of the seam, the two soles fit flat together without any intermediate packing or filling of cork or similar composition as usual and, when so fitted and stitched, the outsole is flat across the ball of the foot as the transverse curvature of the last is accommodated by the wedge-like 100 molded insole. This gives the shoe a broad flat bearing extending across the entire foot, making it easier and more comfortable for the wearer and increasing the life of the shoe by distributing the wear over a greater area.

For all intents and purposes the buffing operation may be said to adapt the insole, which is bent to fit the last, to fit flat against a transversely unbent outsole without intermediate filling of any kind. The thin sectioned piece showing between the two soles constitutes a 105

sheet of waterproof tar paper 16, which in no way affects the problem of maintaining the shape of the shoe.

The triangular sole leather welt 9 cemented 5 in the channel groove is in no sense regarded as a sole filler and the expression "without the use of intermediate filler" is used with this meaning.

With the solid foundation formed by the 10 shaped insole supported directly by the flat outsole, there is no possibility of the insole sagging into a recess beneath it, as is commonly done when the weight of the wearer compacts and displaces forwardly and rearwardly the cork or other composition filler between the insole and the outsole of shoes as ordinarily constructed. Such sagging of the insole increases the sectional area of the shoe as 15 a container so that it no longer restrains the foot against lateral displacement and leaves the arch of the foot unsupported, creating a tendency to broken arches, while the more rigid seams stand as raised ridges to wear callouses at the edges of the foot.

20 All of this is overcome in the shoe of this invention by the rigid or non-compressible and non-displaceable solid wall of varying thickness formed by the two soles fitting together in face to face contact, for the shape produced 25 by the molding of the insole to the last is permanently retained by the reinforcement backing afforded by the outsole bearing directly thereagainst across the entire width of the

shoe. These easily sloping surfaces of the molded insole produce a naturally fitting cavity in which the ball of the foot is retained against lateral displacement without tendency for the foot to stretch the upper and therefore without causing overrunning of the upper. The shoe retains its shape as well as its fit while the walking surface remains level and wear is retarded by being distributed over a greater surface.

35 What I claim as new and desire to secure by Letters Patent is:

40 1. In a shoe, an insole shaped to a last to have its upper surface correspond with the curvatures of the bottom of the last, an upper and a welt stitched thereto, said insole being reduced and flattened at its lower surface beneath the high spot of the last corresponding with the ball of the foot, and a sole member 45 fitted thereto and stitched to the welt with the flat surface of the insole directly bearing thereon.

50 2. In a shoe, an insole increasing in thickness forwardly and rearwardly and toward either side from a point corresponding with the ball of the foot and provided with a shouldered channel, an upper and welt stitched to the shouldered channel of the insole, a triangular sole-leather welt secured within the channel groove, and another sole secured in 55 face to face contact with the insole.

55 In testimony whereof, I affix my signature.
GEORGE E. MUSEBECK.
